CLAIM

The ornamental design for a dual packaging tray, as shown and described.

DESCRIPTION

FIG. 1 is a top perspective view of an upper member of the dual packaging tray showing the new design;

FIG. 2 is a top perspective view of the upper member of the dual packaging tray rotated 180 degrees relative to FIG. 1;

FIG. 3 is a top plan view of the upper member of the dual packaging tray;

FIG. 4 is a bottom plan view of the upper member of the dual packaging tray;

FIG. 5 is a bottom perspective view of the upper member of the dual packaging tray;

FIG. 6 is a bottom perspective view of the upper member of the dual packaging tray rotated 180 degrees relative to FIG. 5;

FIG. 7 is an elevational view of a side of the upper member of the dual packaging tray, the opposing side being identical thereto;

FIG. 8 is an elevational view of an end of the upper member of the dual packaging tray, the opposing side being identical thereto;

FIG. 9 is a top perspective view of a lower member of the dual packaging tray;

FIG. 10 is a top perspective view of the lower member of the dual packaging tray rotated 180 degrees relative to FIG. 9;

FIG. 11 is a top plan view of the lower member of the dual packaging tray;

FIG. 12 is a bottom plan view of the lower member of the dual packaging tray;

FIG. 13 is a bottom perspective view of the lower member of the dual packaging tray;

(Continued)

FIG. 14 is a bottom perspective view of the lower member of the dual packaging tray rotated 180 degrees relative to FIG. 13;
 FIG. 15 is an elevational view of an end of the lower member of the dual packaging tray;
 FIG. 16 is an elevational view of the opposing end of the lower member of the dual packaging tray;
 FIG. 17 is an elevational view of a side of the lower member of the dual packaging tray;
 FIG. 18 is an elevational view of the opposing side of the lower member of the dual packaging tray;
 FIG. 19 is a top perspective view of the dual packaging tray with the upper member combined with the lower member;
 FIG. 20 is a bottom perspective view of the dual packaging tray with the upper member combined with the lower member;
 FIG. 21 is a top perspective view of the dual packaging tray with the upper member separated from the lower member;
 FIG. 22 is a top perspective view of the dual packaging tray with the upper member separated from the lower member, the dual packaging tray being rotated 180 degrees relative to FIG. 21;
 FIG. 23 is a bottom perspective view of the dual packaging tray with the upper member separated from the lower member;
 FIG. 24 is a bottom perspective view of the dual packaging tray with the upper member separated from the lower member, the dual packaging tray being rotated 180 degrees relative to FIG. 23;
 FIG. 25 is an elevational view of an end of the dual packaging tray;
 FIG. 26 is an elevational view of the opposing end of the dual packaging tray;
 FIG. 27 is an elevational view of a side of the dual packaging tray; and,
 FIG. 28 is an elevational view of the opposing side of the dual packaging tray.
 The broken lines are shown for the purpose of illustrating parts of the article that form no part of the claim.
